(74) Attorney, Agent, or Firm — David A. Burge

(57) **CLAIM**

I claim the ornamental design for a combination controlled cash bag lock, substantially as shown and described.

DESCRIPTION

FIG. 1 is a top, rear and left side perspective view of a combination controlled cash bag lock showing my new design;

FIG. 2 is a reversed top plan view thereof;

FIG. 3 is a front elevational view thereof, it being understood that the rear elevational view is a mirror image thereof;

FIG. 4 is a left side elevational view thereof;

FIG. 5 is a right side elevational view thereof;

FIG. 6 is a bottom plan view thereof; and,

FIG. 7 is an enlarged left side elevational view thereof.

The broken line environment is for illustrative purpose only and forms no part of the claimed design. References used herein as front, rear, left, right; top and bottom are not meant for any particular in-use orientation and may be changed for different orientation of the claimed design as chosen by the user.
